UNITED STATES PATENT OFFICE.

SAMUEL W. GORDON, OF NEWARK, NEW JERSEY, ASSIGNOR OF ONE-HALF TO HENRY M. BRANT, OF NEWARK, NEW JERSEY.

UNIVERSAL STERILIZING-STOP-COCK DEVICE.

1,272,943.

Specification of Letters Patent. Patented July 16, 1918.

Application filed March 30, 1915. Serial No. 18,075.

To all whom it may concern:

Be it known that I, SAMUEL W. GORDON, a citizen of the United States, residing at Newark, in the county of Essex and State 6 of New Jersey, have invented certain new and useful Improvements in Universal Sterilizing-Stop-Cock Devices; and I do hereby declare the following to be a full, clear, and exact description of the invention, such as 10 will enable others skilled in the art to which it appertains to make and use the same.

The invention relates to improvements in stop cocks.

The object of the present invention is to 15 improve the construction of stop cocks and to provide a simple, practical, and comparatively inexpensive, universal sterilizing stop cock adapted to control the supply of steam, hot water and cold water and equipped with 20 means for adjustably maintaining the parts in a tight condition and capable of affording ready access to the adjusting means when desired.

With these and other objects in view the 25 invention consists in the construction and novel combination and arrangement of parts hereinafter fully described, illustrated in the accompanying drawings and pointed out in the claim hereto appended, it being understood that various changes in the form, proportion and minor details of construction 30 may be resorted to without departing from the spirit or sacrificing any of the advantages of the invention.

35 In the drawing

Figure 1 is a sectional view of a sterilizing stop cock constructed in accordance with this invention and shown applied to a sink,

Fig. 2 is an enlarged longitudinal sectional view through a modified form of the 40 sterilizing stop cock.

Like numerals of reference designate corresponding parts in the several views of the drawings.

45 In the accompanying drawing in which is illustrated the preferred embodiment of the invention, the universal sterilizing stop cock which is designed for use for sterilizing instruments and analogous purposes 50 comprises in its construction an outer casing 1 of tubular form tapered forwardly or outwardly and provided at the top with a steam inlet nipple 2 and having at the bottom a hot water inlet nipple 3 and a cold water 55 inlet nipple 4. These nipples are shown in

the accompanying drawing as formed integral with the casing but they may consist of separate pieces threaded into the casing. The nipple 2 is interiorly threaded for the reception of the threaded end 5 of a steam 60 pipe 6 which may be connected with any suitable source of steam supply. The nipples 3 and 4 are interiorly threaded for the reception of the threaded ends 7 and 8 of hot water and cold water pipes 9 and 10 65 connected with any suitable source of supply.

Within the casing 1 is arranged the rotary tubular valve 11 provided with ports or openings 12, 13 and 14 adapted to be brought into register with the nipples 2, 3 and 4 and 70 as the openings 12, 13 and 14 are located at different points around the rotary tubular member two of them will be out of register with their coacting nipples when one is brought into register with its nipple. By 75 this construction either hot water, cold water or steam may be supplied to the nozzle 15. The rotary tubular member has an outer exteriorly threaded end 16 which is arranged within an enlarged terminal portion 17 of 80 the casing and the said nut is adapted to bear against the coiled spring 18 interposed between the nut and the shoulder 19 formed by the inner end of the enlargement 17, whereby the spring is adapted to hold the 85 tapered rotary member into tight engagement with the tapered casing to form a water tight joint or connection between the said parts. Should the tubular member become loose the nut is adapted to be tightened to 90 increase the tension of the spring. The nut which is preferably of octagonal form is arranged within the extension 17 and the latter is exteriorly threaded at 20 to receive an enlarged cap portion 21 of the nozzle 15. The 95 nozzle 15 by screwing on the exterior of the enlargement 17 is adapted to be readily removed to afford instant access to the adjusting means for maintaining the tubular member in proper engagement with the casing. 100 The tubular member is provided at its enlarged end with a polygonal extension 22 adapted to receive an operating handle 23 secured by a pin or other suitable fastening device to the said polygonal extension 22 and 105 provided with a socket or opening 25 for the reception of the same. The universal sterilizing stop cock is adapted to be arranged over a sink 26 as illustrated in Fig. 1 of the drawing with the nozzle in a projecting po- 110

sition at one end of the stop cock and the handle at the opposite end of the same in convenient position for ready operation to discharge either steam or hot or cold water 5 as required.

In Fig. 1 is illustrated another form of the invention in which the outer casing 27 is oppositely tapered from that shown in Fig. 2 and the enlarged end is interiorly threaded 10 at 28 for the reception of a threaded portion 29 of a nozzle 30. In this form of the invention which is simpler than that illustrated in Fig. 2 the spring for urging the tapered rotary member into tight engagement 15 with the casing is omitted.

The nozzle 30 in this form of the invention constitutes an adjusting means for maintaining the tapered rotary member in tight engagement with the casing.

What is claimed is:

A valve casing having an inlet opening, a core rotatable therein, having an inlet port and an axial outlet in one end, a nut threaded to the said end of the core, a spring bearing against the nut and casing for establishing a 25 tight fit between the core and casing and still permit free rotation of the core, a screw threaded extension on one end of said casing and overlying the spring and nut, a spout, and an internally screw threaded enlarged 30 portion on said spout for connection with the extension.

In testimony whereof I affix my signature in presence of two witnesses.

SAMUEL W. GORDON.
